CLAIM

The ornamental design for an elliptical baluster, as shown and described.

DESCRIPTION

FIG. 1 is a perspective view of an elliptical baluster showing my new design shown in a straight railing that is perpendicular to the baluster.

FIG. 2 is a perspective view of an elliptical baluster showing my new design shown in an angled railing that is angled to the baluster; and,

FIG. 3 is a sectional view taken along line III-III of FIG. 1. In the drawings, the broken lines represent an environment in which the claimed design is embodied and form no part of the claimed design.
